UNITED STATES PATENT OFFICE

JAMES WILSON WELSH, OF PROVIDENCE, RHODE ISLAND, ASSIGNOR TO THE WELSH MANUFACTURING COMPANY, OF PROVIDENCE, RHODE ISLAND, A CORPORATION OF RHODE ISLAND

MECHANICAL PENCIL

Application filed March 21, 1929. Serial No. 348,824.

The present invention relates to marking devices, and more particularly to mechanical pencils.

An object of the invention is to improve upon devices of the above-described character, to the end that their efficiency may be increased, their construction simplified and their cost of manufacture reduced. Other and further objects will be explained hereinafter and will be particularly pointed out in the appended claims.

In the accompanying drawings, illustrating a preferred embodiment of the present invention, Fig. 1 is an elevation; Fig. 2 is a central longitudinal section taken through the casing and the cap, substantially upon the line 2—2 of Fig. 1, looking in the direction of the arrows; Fig. 3 is a section, upon a larger scale, taken upon the line 3—3 of Fig. 2, looking in the direction of the arrows; Fig. 4 is a fragmentary, enlarged view of the body of the pencil, with the casing removed, the parts being shown in positions similar to those of Fig. 2; Figs. 5 and 6 are sections taken substantially upon the lines 5—5 and 6—6 of Fig. 4, looking in the directions of the arrows; Figs. 7 and 8 are views, upon different scales, of details; Fig. 9 is a view of a further detail; and Fig. 10 is a view of a modification.

The pencil-carrying body is housed in a casing 2 (Figs. 1, 2 and 3). The pencil may be retained in the owner's pocket by a clip 6 having a terminal prong 8 and an intermediate disposed prong 9 (Figs. 2 and 9) extending through openings 10 and bent over against the inner wall 12 of the casing. The clip 6 is shown in Fig. 9 before assembly with the casing 2. In such condition, the prongs are shown extending medially of the sides 11 and 13 of the clip 6 at right angles to the body of the clip, the prong 9 being cut out of the body of the clip. Where metal casings 2 are used, the openings 10 are previously formed in the casing, but when celluloid or other suitable non-metallic casings 2 are employed, the prongs may drive their own openings into the casing.

The lead or other marker 14 projects from the forward, conical end of the casing and is

gradually fed forward, as it is used up, by rotary feed mechanism hereinafter to be described. An eraser 16 at the other or rear end of the pencil is ordinarily protected against dirt and the like by a cap 18, but may be put into service when the cap is removed.

The lead 14 is frictionally clutched or held by a plunger tube 20 through one end 22 of which it projects, as will be understood more particularly from Figs. 2, 3 and 4. The tube 20 is slidably mounted in a slotted tube 24. The lower end 26 of the slotted tube 24 may rest in a guide groove 28 at the lower end of the casing, as will be understood from Fig. 2. The guide groove 28 may, however, be formed in a separate metal piece 29 that is screwed into the lower end of the casing 2 at 31, particularly if the casing 2 is of celluloid or other non-metallic material. The lower end 22 of the marker-holding tube 20 is normally within the slotted tube 24, as shown in Figs. 2 and 3, but may be projected through the lower end 26 of the slotted tube 24, as shown in Fig. 4, towards the end of its feed movement through the slotted tube 24, as hereinafter described. This happens, of course, when the lead 14 has become nearly completely used up, and the small, still-remaining, portion of the lead is then forced out of the end 22 of the clutch tube 20 by a marker plunger or push rod 32 that is slidably mounted in the clutch tube 20. Normally, as will be described hereinafter, the marker-holding or clutch tube 20 and the plunger push rod 32 move longitudinally through the slotted tube 24 as a unit, but at their lower limit of movement, the clutch tube 20 is held stationary and the push rod 32 is advanced therethrough, into the position illustrated in Fig. 4, to expel the lead.

Upon a reverse movement of the parts, on the other hand, the push rod 32 first withdraws into the clutch tube 20, to permit the insertion of a new lead into the same, and then the clutch tube 20, the lead held thereby and the plunger push rod 32 may be withdrawn into the slotted tube 24 in readiness for a new advance of the lead 14. It is thus possible to have as much lead projecting from the casing as desired, and if the lead should, by 100

any chance, be advanced too far out of the casing, all that is necessary is to retract the push rod 32 and the holding tube 20 as a unit, carrying the lead with it, until just so much lead only projects from the casing as is desired. The lead may similarly be withdrawn into the casing to protect it against breakage when the pencil is not in use. The plunger push rod 32 may be advanced through the end 22 of the holding tube 20 up to the very end 22 of the tube, so that practically the very last tip of the lead 14 may be used up, for the tube 20 will continue to clutch the lead 14 even though only a very small portion of it is left.

The tube 20 is intermediately provided, near its upper end, with a projection 33. A portion of the tube 20 just above the projection 33 is slotted longitudinally at 40 for a considerable distance to permit free sliding movement between the walls of the slot of a projection 34 that is provided upon the push rod 32. The purpose of the slot 42 in the slotted tube 24 is to receive the projections 33 and 34 and keep them alined in the slot 42, thereby permitting free slidable movement through the slotted tube 24 of the plunger tube 20 and the plunger push rod 32. A preferred method of manufacturing the tube 20 is to die a suitably shaped blank out of sheet steel, and then to fold it, as shown. The upper end 54 of the tube 20 is closed to prevent the projection 34 from riding out of the slot 40.

The preferred mechanism for advancing and retracting the plunger holding tube 20 and the plunger push rod 32 will now be described. The projections 33 and 34 of the tube 20 and the push rod 32, respectively, are adapted to be engaged by a helical or spiral thread 36 upon a rotatable sleeve 38 that is mounted to enclose the slotted tube 24. As will be explained hereinafter, the spirally threaded sleeve 38, though rotatable relative to the slotted tube 24, is held against longitudinal movement relative to the slotted tube 24. The sleeve 38 may be made in any desired manner, as by spirally coiling a stamped-out, flat, sheet-metal blank. As illustrated in Figs. 2 and 3, the projections 33 and 34 normally engage spaced portions of the spiral thread 36, so that the projections 33 and 34 will normally remain separated from each other by a constant distance. As the sleeve 38 is rotated about the slotted tube 24, therefore, the holding tube 20 and the push rod 32 will be advanced or retracted through the slotted tube 24 as a unit, according to the direction of rotation of the sleeve 38. The projections 33 and 34 will slide freely through the slot 42 during such rotation of the spirally threaded sleeve 38. To advance or retract the lead 14, therefore, all that is necessary is to rotate the spiral sleeve 38, holding the slotted tube 24 stationary.

According to the preferred construction, the spiral sleeve 38 is adapted to be rotated by securing it to a manually rotatable tube 46 that projects through the casing at the rear or eraser end of the pencil. This may be effected in any desired way, preferably by inserting the upper end 44 of the tube 38 in the lower end 45 of the tube 46, and soldering or swedging the parts together. To bring this about, of course, the diameters of the parts 44 and 45 should preferably be such that the former will just fit into the latter. As the cap 18 is fitted frictionally on the upper enlarged or expanded end 47 of the tube 46, the lead 14 may be advanced or retracted at will by rotating the cap 18 in one direction or the other, while holding the slotted tube 24 against rotation. The purpose of enlarging the tube 46 at 47 is two fold: first, the tube 46 is enabled to fit better in the casing 2, as shown in Fig. 2; and secondly, it provides a seat for the eraser 16. Or, the tube 46 may be of enlarged diameter to start with, and the end 45 of the tube may, in that event, be reduced in diameter. The enlarged portion 47 of the tube 46 is slotted at 49, to provide a resilient holding action upon the eraser 16.

It is now necessary to describe how the slotted tube 24 is held against rotation during the rotatable movement of the sleeve 38. After the parts thus far described, with the exception of the cap 18 and the casing 2, are assembled together, they are inserted as a unit in a barrel 51. The barrel 51 is substantially of the same length as the sleeve 38 and provided with two longitudinally disposed slots 53 and 55, and an end plate 57 provided with an opening 59. The slots 53 and 55 extend substantially throughout the length of the barrel 51 and the end plate 52 is bent over at right angles to the axis of the barrel 51. The slotted tube 24 extends through the opening 59, permitting the lower end of the spirally threaded sleeve 38 to engage against the end plate 57. The opening 59 is provided with a key lock or other projection 68 to engage against the slot 42 of the slotted tube 24 to prevent the tube 24 from rotating relative to the end plate 57. A collar 61 is slipped over the lower end 26 of the slotted tube 24 until it contacts with the end plate 57, and is secured in place in any desired manner. A very effective securing means consists in merely striking out, or expanding outward, at 63, a portion of the wall of the tube 24 just below the collar 61.

The parts thus far described, except for the casing 2 and the cap 18, will be held together as a unit, if the slotted tube 24 is caused to be held in a place. The upper end of the slotted tube 24 is therefore provided with a plug having a shank 65 and a head 67. The plug may take the form of an ordinary rivet. The shank 65 is secured in the slotted tube 24

in any desired manner, as by soldering. The head 67 is of greater diameter than the diameter of the slotted tube 24, and is disposed outside of the slotted tube in order that it may engage against the upper end 44 of the sleeve 38. The slotted tube 24 is thus prevented from slipping longitudinally out through the opening 59 and the parts are held together as a unit.

10 The rivet serves a further purpose in that it acts as a bottom for the tube 46. The tube 46 may then serve as a chamber for extra leads 14. To remove an extra lead 14, all that is necessary is to unseat the eraser 16, thereby affording access to the lead chamber.

To permit inserting this unit into the casing 2, the slot 53 of the barrel 51 is made wide enough so that the prongs 8 and 9 may readily be passed therethrough. The purpose of the other slot 55 is to strengthen the spring action of the spring walls 69 and 71 that are formed on both sides of the slots 53 and 55, without causing these spring walls to produce a bulge in the casing 2. It is, therefore, made narrower than the slot 53. The walls 69 and 71 are bent outward to engage frictionally against the inner walls of the casing 2. As the walls 69 and 71 are substantially as long as the sleeve 38, they bind against the inner cylindrical walls of the casing 2 throughout a substantial area above the conical end of the casing. Sufficient spring tension is thus provided to hold the unit frictionally in position in the casing during the rotation of the sleeve 38, but the unit may readily be withdrawn from the casing, in opposition to the spring tension of the spring walls 69 and 71, by pulling outward upon the portion 47 of the tube 46.

40 In operation, the turning movement of the cap 18 will be communicated to the spirally threaded sleeve 38. The projections 33 and 34 will thus be advanced and retracted according to the direction of rotation of the cap 18, carrying the lead 14 with them as a unit. At the forward limit of slidable movement of the holding tube 20, the projection 33, being nearer to the end plate than the projection 34, will ride off the open end 58 of the thread 36, and become seated in a depressed stop 73 that is provided in the end plate 57. As the holding tube 20 can not advance beyond that point, further rotative movement of the sleeve 38 will cause the projection 34 to advance toward, and into engagement with, the stop 33, as shown in Fig. 4, with the result that, as the push rod 32 advances through the holding tube 20, it will expel the lead. A reverse rotatable movement of the sleeve 38 will cause, first, the projection 34, and then, the projection 33, to engage with the thread 36, after which a new lead may be inserted in the end 22 of the holding tube 20.

As an alternative construction, the wall at 65 the lower end of the sleeve 38 may be cut away

at a point external to the thread to provide a stop 75, thus to prevent the projection 33 from riding out beyond the control of the thread 36 after the lead has been expelled.

Other modifications, too, will occur to persons skilled in the art, and all such are considered to be included within the scope of the invention.

What is claimed is:

1. A device of the class described having, in combination, a marker plunger having a projection, a longitudinally slotted tube within which the plunger is slidably mounted, the longitudinal slot of the tube permitting free sliding movement of the projection between the walls of the slot, a plug having a shank secured in one end of the slotted tube and a head of greater diameter than the diameter of the slotted tube disposed outside of the slotted tube, the head being continuous so as to close the slot of the tube, whereby the head may serve as the closed bottom of a receptacle, a sleeve enclosing the slotted tube with the head of the plug engaging an end of the sleeve, the sleeve being rotatable relative to the slotted tube, means cooperating with the head of the plug to hold the sleeve and the slotted tube against relative longitudinal movement, the sleeve having a spiral thread adapted to engage the projection to advance and retract the plunger according to the direction of relative rotation of the sleeve and the slotted tube, a casing, and means for holding the slotted tube against rotative movement in the casing, whereby rotative movement of the sleeve in the casing will effect longitudinal movement of the plunger in the slotted tube.

2. A device of the class described having, in combination, a marker plunger having a projection, a longitudinally slotted tube within which the plunger is slidably mounted, the longitudinal slot of the tube permitting free sliding movement of the projection between the walls of the slot, a plug having a shank secured in one end of the slotted tube and a head of greater diameter than the diameter of the slotted tube disposed outside of the slotted tube, a sleeve enclosing the slotted tube with the head of the plug engaging an end of the sleeve, the sleeve being rotatable relative to the slotted tube, means cooperating with the head of the plug to hold the sleeve and the slotted tube against relative longitudinal movement, the sleeve having a spiral thread adapted to engage the projection to advance and retract the plunger according to the direction of relative rotation of the sleeve and the slotted tube, a chamber tube, the end of the sleeve near the plug being secured in an end of the chamber tube, whereby the head of the plug forms a closed bottom for the chamber tube, and a casing in which the slotted tube is held against rotative movement, with the other end of the chamber tube projecting

through an end of the casing, whereby rotative movement of the chamber tube in the casing will effect a rotative movement of the sleeve relatively to the slotted tube and thereby effect longitudinal movement of the plunger in the slotted tube.

3. In a device of the class described having a marker plunger, a casing, a clip, and means extending through the inner walls of the 10 casing for holding the clip on the casing, means for advancing and retracting the plunger in the casing including a barrel having two longitudinal slots, whereby spring walls are formed between the slots, one of 15 the slots being wide enough to permit the extending means to be passed therethrough when the barrel is slid into the casing, and the other slot being narrower than the said one slot, whereby the spring walls are made 20 relatively wide so that they are adapted to engage frictionally against the inner walls of the casing with sufficient spring tension to hold the plunger frictionally in position in the casing, but without spring tension great 25 enough to produce a bulge in the casing.

4. As an article of manufacture, a barrel having two longitudinal slots, whereby spring walls are formed between the slots, one of the slots being wide enough to permit an article of substantial width to be passed therethrough, the other slot being narrower than the said one slot, whereby the spring walls, are made relatively wide, the barrel having an end plate bent over at an angle to the axis 30 of the barrel, and the end plate being provided with an opening.

5. As an article of manufacture, a sheet-metal barrel having two longitudinal slots, whereby spring walls are formed between 40 the slots, the barrel having an end plate bent over at an angle to the axis of the barrel, and the end plate being provided with an opening, a slotted marker-plunger-holding tube extending through the opening and an elevated 45 stop, the plate having means for preventing rotation of the slotted marker-plunger-holding tube.

6. A device of the class described having, in combination, a marker plunger having a 50 projection, a longitudinally slotted tube within which the plunger is slidably mounted, the longitudinal slot of the tube permitting free sliding movement of the projection between the walls of the slot, a plug having a shank 55 secured in one end of the slotted tube and a head of greater diameter than the diameter of the slotted tube disposed outside of the slotted tube, a sleeve enclosing the slotted tube with the head of the plug engaging an end 60 of the sleeve, the sleeve being rotatable relative to the slotted tube and having a spiral thread adapted to engage the projection to advance and retract the plunger according to the direction of relative rotation of the sleeve 65 and the slotted tube, a barrel in which the

sleeve is rotatably disposed, the barrel having an end plate provided with an opening through which the slotted tube extends, means engaging the end plate and cooperating with the head of the rivet to hold the 70 sleeve and the slotted tube against relative longitudinal movement, whereby rotative movement of the sleeve relatively to the barrel will effect longitudinal movement of the plunger in the slotted tube, and means for holding the slotted tube from rotation with respect to the barrel.

7. A device of the class described having, in combination, a marker-holding tube having a projection, a marker plunger in the holding tube having a projection alined with the holding-tube projection, a longitudinally slotted tube within which the holding tube with the plunger therein is slidably mounted, the longitudinal slot of the slotted tube permitting free sliding movement of the projections between the walls of the slot, a plug having a shank secured in one end of the slotted tube and a head of greater diameter than the diameter of the slotted tube disposed outside of the slotted tube, a sleeve enclosing the slotted tube with the head of the plug engaging an end of the sleeve, the sleeve being rotatable relative to the slotted tube and having a spiral thread spaced portions of which are adapted to engage the alined projections to advance and retract the holding tube and the plunger therein according to the direction of relative rotation of the sleeve and the slotted tube, a barrel in which the sleeve is 90 rotatably disposed, the barrel having an end plate engaging the other end of the sleeve and provided with an opening through which the slotted tube extends, a collar upon the slotted tube in engagement with the end plate, means upon the slotted tube engaging the collar and cooperating with the head of the rivet to hold the sleeve and the slotted tube against relative longitudinal movement, whereby rotative movement of the sleeve relatively to the barrel will effect longitudinal movement of the plunger and the holding tube in the slotted tube, and means for holding the slotted tube from rotation with respect to the barrel.

8. A device of the class described having, in combination, a marker plunger having a projection, a longitudinally slotted tube within which the plunger is slidably mounted and having a projection near one end, the longitudinal slot of the slotted tube permitting free sliding movement of the marker-plunger projection between the walls of the slot, a sleeve enclosing the slotted tube, the sleeve having a spiral thread extending therethrough adapted to engage the marker-plunger projection to advance and retract the plunger according to the direction of relative rotation of the sleeve and the slotted tube, a barrel in which the sleeve is rotatably 120 disposed.

- disposed, a casing, means disposed near the other end of the slotted tube and cooperating with the slotted-tube projection to hold the plunger, the slotted tube, the sleeve and the barrel together as a unit against relative longitudinal movement but permitting relative rotative movement between the sleeve and the slotted tube, and means for effecting rotative movement of the sleeve relative to the slotted tube in the casing to produce longitudinal movement of the plunger in the slotted tube. 5
9. A device of the class described having, in combination, a marker plunger having a projection, a longitudinally slotted tube within which the plunger is slidably mounted and having a projection near one end, the longitudinal slot of the slotted tube permitting free sliding movement of the marker-plunger projection between the walls of the slot, a sleeve enclosing the slotted tube, the sleeve being rotatable relative to the slotted tube but being held against longitudinal movement relative to the slotted tube, the sleeve having a spiral thread extending there-through adapted to engage the projection to advance and retract the plunger according to the direction of relative rotation of the sleeve and the slotted tube, a chamber tube, one end of the sleeve being secured in an end 10 of the chamber tube, a barrel in which the sleeve is rotatably disposed, a casing, and means disposed near the other end of the slotted tube and cooperating with the slotted-tube projection to hold the plunger, the tubes, 15 the sleeve and the barrel together as a unit against relative longitudinal movement but permitting relative rotative movement between the sleeve and the slotted tube, and the other end of the chamber tube projecting 20 through one end of the casing, whereby rotative movement of the chamber tube in the casing will effect a rotative movement of the sleeve relatively to the slotted tube and thereby effect longitudinal movement of the plunger 25 in the slotted tube. 25
10. A device of the class described having, in combination, a marker plunger having a projection, a longitudinally slotted tube within which the plunger is slidably mounted, the longitudinal slot of the slotted tube permitting free sliding movement of the projection between the walls of the slot, a sleeve enclosing the slotted tube, the sleeve having a spiral thread adapted to engage the projection to advance and retract the plunger according to the direction of relative rotation of the sleeve and the slotted tube, a barrel in which the sleeve is rotatably disposed, the barrel having an end plate provided with an opening through which the slotted tube extends, means for effecting rotative movement of the sleeve relatively to the barrel to effect longitudinal movement of the plunger 30 in the slotted tube, two means respectively provided near opposite ends of the slotted 35 tube and respectively engaging the end plate and the opposite end of the sleeve for holding the parts together as a unit against relative longitudinal movement but permitting relative rotative movement between the sleeve and the slotted tube, and a casing, the unit being adapted to be inserted in the casing. 70
